[57] CLAIM

The ornamental design for a bottle, as shown and described.

DESCRIPTION

FIG. 1 is a side elevational view of the bottle showing my new design;

FIG. 2 is an elevational view looking from the left at FIG. 1;

FIG. 3 is an elevational view looking from the right at FIG. 1; and

FIG. 4 is a top plan view.

The side not shown is a mirror image of the side shown.
